UNITED STATES PATENT OFFICE.

JOSEPH W. SHARP, JR., OF PHILADELPHIA, PENNSYLVANIA, ASSIGNEE TO HAINES,
JONES & CADBURY INC., OF PHILADELPHIA, PENNSYLVANIA.

WATER-CLOSET.

1,110,831.

Specification of Letters Patent. Patented Sept. 15, 1914.

Application filed May 13, 1914. Serial No. 838,303.

To all whom it may concern:

Be it known that I, JOSEPH W. SHARP, Jr., a citizen of the United States, residing at Philadelphia, in the county of Philadelphia 5 and State of Pennsylvania, have invented new and useful Improvements in Water-Closets, of which the following is a specification.

The present invention relates to water closets, and has for its object to provide a closet in which the flushing rim is interrupted at the rear of the bowl to form an elongated seat opening at the top of the bowl; in which the proper ventilation of the bowl 15 of the closet is had by conducting a venting passage from the bowl at a point between the interrupted ends of the flushing rim in a straight line directly rearward through the closet; in which the venting passage has a 20 dam to offset overflow from the bowl into the venting passage and has an overflow and room venting opening located in the lower side of the venting passage beyond the dam to admit of the escape of the overflow should 25 the same pass the dam; in which the venting passage has a second dam beyond the overflow opening to insure the discharge of the overflow through said opening and prevent any possibility of fouling the venting flue 30 which is located in the wall of the building, and to which access cannot readily be had for the purpose of cleansing, the second dam constituting a shoulder against which the inner end of the connecting pipe between 35 the venting flue and the venting passage is secured; and in which a separate flushing means is provided for the rear wall of the bowl between the ends of the interrupted rim and separate from the rim to wash the 40 outer side of the upleg of the siphon passage and back wall of the bowl.

Other objects and advantages of this invention will appear from the following detail description of the present embodiment 45 of the invention, the same being shown in the accompanying drawings in which—

Figure 1 is a vertical central section taken through a closet constructed in accordance with this invention and showing in side elevation a low down tank connected thereto. Fig. 2 is a top plan view of the closet having the tank removed. Fig. 3 is a similar view having the seat removed and showing in dotted lines the various ducts leading 50 from the tank connection. Fig. 4 is a view similar to Fig. 1 but on a reduced scale, of

a slight modification of the closet, wherein the vent duct is omitted. Fig. 5 is a top plan view of the same having the tank and seat removed.

Referring to these drawings, wherein like parts are designated by similar characters of reference throughout the several views, 60 10 designates the bowl of the closet which is of the ordinary siphon type having the usual "trap" and hopper, siphon passage, and waste pipe connection. Around the top of the hopper or bowl of the closet is arranged in the usual manner the flushing rim 11, the same being of ordinary construction with the exception that at the rear of the bowl the rim is interrupted as shown to 65 advantage in Figs. 2 and 3 to provide an opening or space 12 constituting an elongation of the seat opening. The flushing rim 70 terminates at the opposite sides of the opening 12, and the opposite sides of the flushing rim are supplied with water through the independent ducts 31 located in the opposite sides of the closet and connecting 75 with the supply passages 26 extending to the flushing inlet 14. The front wall 15 of the upleg of the siphon passage constitutes in part the rear wall of the bowl or hopper, and is exposed by the provision of the opening 12. For the purpose of flushing the 80 front wall 15 of the siphon passage a flushing chamber 16 is formed in the rear of the closet preferably on top of the siphon passage and provided with flushing openings 85 17 located immediately at the top of the wall 15, or the flushing may be accomplished by the perforations in the water passages 26. The flushing chamber 16, 90 as shown in dotted lines in Fig. 3, connects at its opposite ends with the water passages 26, the latter also supplying water to the flushing rim 13 through the ducts 31. This peculiar construction of the closet is 95 had for the purpose of providing a vent 100 passage 18 leading from a point near the top of the bowl directly rearward in a straight line and terminating preferably at the rear of the closet in a horn 19 to which is attached the thimble 20 leading to the 105 usual vent flue in the wall of the building. If desired the thimble 20 may be omitted and the horn 19 finished against the wall in which the vent flue is located. The vent 110 passage 18 is raised immediately above the top of the siphon passage, the top of the flushing chamber 16 constituting the lower

wall of the vent passage at this point and also providing a dam in the vent passage adapted to prevent overflow from the bowl or hopper into the vent passage 18.

5 Depending from the top of the closet immediately beyond the ends of the flushing rim is an apron 21, constituting the rear wall of the opening 12, and serving as a guard. The vent passage 18 is carried abruptly down into its normal plane immediately behind the dam and opens into the horn 19. At about the point of mergence of the vent passage 18 into the horn 19, an overflow opening 22 is formed in the lower wall of the vent passage and is adapted to permit the escape of any overflow which may pass the dam. Immediately above the rear end of the vent passage 18 is located the inlet opening 14, the latter having connection with a tank pipe 23 leading from a tank 24. The vent passage 18 is dropped abruptly behind the dam for the purpose of accommodating the inlet 14 and thus providing a tank connection which lies in the plane of the top of the bowl. The horn 19, comprising the rear termination of the vent passage 18, is provided in its lower side with a raised shoulder or dam 25 which is located rearwardly of the outlet opening 22, 20 the shoulder or dam 25 forming a second dam to insure the discharge of the overflow, if any should occur, through the opening 22 and thus positively prevent the fouling of the vent flue in the wall, and also forming 25 a stop or shoulder determining the position of the inner end of the thimble 20 which leads from the horn 19 to the vent flue in the wall. The inlet 14 is provided with one or more water passages 26, the present illustration showing two separate water passages although it is to be understood that any number found desirable may be used, the pair of passages shown leading down at the opposite sides of the closet to a jet 40 chamber 27 having in its upper wall a relatively small jet opening 28, through which a stream of water is adapted to flow and be directed upwardly into the upleg of the siphon passage.

45 From Figs. 1 and 3 of the drawings it will be noted that the supply passages shown in connection with the present embodiment of the invention are relatively wide, the same extending from the rear of the closet to a point substantially in line with the rear wall of the bowl or hopper, the supply passages 26 tapering down and opening into the opposite sides of the jet chamber 27. Each of the passages 26 is provided with a dia- 50 phragm 32 extending downwardly and transversely within the passage 26 from the inlet 14 to a point near the bottom of the passage 26, the diaphragm directing the water from the inlet 14 into the bottom of the passage 26 and below the normal water level

of the bowl to obtain a quiet and muffled action of the closet by forcing air contained in the passages into the bowl underneath the water normally lying therein. It will also be noted that as the water passages 26 are relatively wide they provide for a refill chamber of relatively large capacity, the water from the passages 26 flowing into the bowl after its siphonic action has ceased. It will be noted that in this structure a bowl vent passage is disclosed which is of a predetermined constant size and that the wall or thimble branches and also the room venting opening may be of variable size.

55 In Figs. 4 and 5 of the drawings there is shown a slight modification of this invention. It may be desired to produce a closet according to this invention without the vent passage 18. In this event a web 15^a is placed between the top of the bowl 10 and the flushing chamber or channel 33 to close the vent passage and, at the same time provide for the desired flushing of the front wall 15 of the siphon passage. In other respects the structure is the same.

90 For the purpose of taking advantage of the elongated seat opening, the closet may be provided with a seat 29 having an elongated seat opening corresponding to the opening at the top of the bowl and secured to the closet in any suitable manner, as by hinges 30.

95 What is claimed is—

1. A bowl of the character described, having an up-leg constituting a part of the rear wall of the bowl, a flushing rim extending around the bowl and terminating at either side of the up-leg whereby to provide an elongated bowl opening, supply ducts for the opposite ends of said rim, and a separate supply duct for the up-leg and rear bowl wall.

100 2. A bowl of the character described having a U-shape flushing rim terminating at the opposite sides of the rear wall of the bowl whereby to provide an elongated opening at the top of the bowl, a separate supply duct for each arm of the U-shape flushing rim, and independent flushing means for the rear wall of the bowl discharging between the ends of said U-shape rim.

105 3. A bowl of the character described having a U-shape flushing rim terminating at the opposite sides of the rear wall of the bowl, means for supplying water to the flushing rim, and independent flushing means for the rear wall of the bowl discharging between the ends of said U-shape rim.

110 4. A device as specified having a hopper, a flushing rim at the upper edge of the hopper terminating at the opposite sides of the rear wall of the hopper, independent supply passages leading to the opposite sides of the flushing rim, a flushing chamber 115

cated at the top of the rear wall of the hopper, and an independent supply passage leading to said flushing chamber.

5. A device as specified having a bowl, an upleg constituting a part of the rear wall of the bowl, a flushing rim extending around the bowl and terminating at the opposite sides of the upleg whereby to provide an elongated bowl opening, supply ducts for 10 the opposite ends of said rim, a supply duct for the upleg, a flushing chamber located adjacent to the top of said upleg and an independent supply duct for said flushing chamber.

15. 6. A device as specified having a hopper, a U-shape flushing rim terminating at the opposite sides of the rear wall of the hopper whereby to provide an elongated opening at the top of the hopper, a separate supply for 20 each arm of the U-shape flushing rim, a flushing chamber located adjacent to the top of the rear wall of the hopper, and an independent supply duct for said flushing chamber.

25. 7. In a device as specified, a bowl having a U-shape flushing rim terminating at the opposite sides of the rear wall of the bowl, a flushing chamber mounted upon the top of the rear wall of the bowl rearwardly of 30 the ends of the flushing rim, and independent supply ducts leading to the opposite arms of said flushing rim and to said flushing chamber for supplying water to the same.

35. 8. In a device as specified a bowl, a flushing rim for the bowl interrupted at its rear side, an apron depending between the interrupted ends of the flushing rim, a horizontal vent passage extending rearwardly 40 from between the ends of the flushing rim to the back of the device, a flushing chamber located at the top of the rear wall of the bowl within said passage and immediately behind said apron whereby to provide a dam in the vent passage, supply ducts 45 for the opposite sides of said flushing rim and independent supply ducts for said flushing chamber.

50. 9. In a device as specified a hopper, a flushing rim at the top of the hopper terminating at the opposite sides of the rear wall of the hopper, a siphon passage in the ware of the device having an upleg con-

stituting the rear wall of the hopper, a flushing chamber disposed at the top of the 55 siphon passage and having flushing apertures opening at the top of said rear wall, supply ducts for the opposite sides of said flushing rim, independent supply ducts for said flushing chamber, and a supply duct 60 for the upleg of said siphon passage.

10. A device as specified having a bowl in the front of the ware thereof, a vent passage leading in a straight line through the ware from the top of the rear wall of the bowl, 65 a flushing rim at the top of the bowl terminating at the opposite sides of the vent passage, a flushing chamber in the bottom of the vent passage at the top of the rear wall of the bowl and constituting a dam in the 70 vent passage, a horn at the rear of the bowl opening to said vent passage and having an overflow and room venting opening in its lower side, and a second dam in said horn rearwardly of said overflow opening to insure 75 the passage of the overflow from the bowl through said opening.

11. A bowl of the character described provided with a bowl trap, a flushing rim at the top of the bowl terminating at the opposite 80 sides of the rear wall thereof, supply passages at the opposite sides of the bowl, diaphragms in said passages adapted to direct the inflowing water into the bottom of said passages below the normal water level of 85 the bowl, and a jet chamber at the bottom of the bowl communicating with said supply passages, said supply passages communicating with the opposite ends of said flushing rim. 90

12. In a device as specified, a bowl, a flushing rim for the bowl interrupted at its rear side, an apron depending between the interrupted ends of the flushing rim, a horizontal vent passage extending rearwardly in 95 a straight line from between the ends of the flushing rim to the rear of the device, and supply ducts for the opposite sides of said flushing rim.

In testimony whereof I have hereunto set 100 my hand in presence of two subscribing witnesses.
